UNITED STATES PATENT OFFICE.

ROBERT McCART, JR., OF EL PASO, TEXAS.

RECORD-FILING CABINET.

1,349,466.

Specification of Letters Patent. Patented Aug. 10, 1920.

Application filed May 13, 1919. Serial No. 296,776.

To all whom it may concern:

Be it known that I, ROBERT McCART, Jr., a citizen of the United States, and a resident of El Paso, in the county of El Paso, 5 and State of Texas, have invented a new and Improved Record-Filing Cabinet, of which the following is a full, clear, and exact description.

It is a well-known fact that no simple, 10 economical and practical record cabinets are upon the market at the present time. The usual filing device consists of a book containing hollow pages for the reception of records, which books are cumbersome and 15 extremely heavy to handle, besides necessitating the expenditure of time, used in locating the record desired.

My invention aims to provide a filing cabinet which at all times will present all 20 of the records contained therein in plain view and in such manner that the title of the same, which may be pasted or otherwise applied to the individual record containers, may be read without stooping.

25 Further my invention aims to provide a filing device which will accommodate records of different sizes, within the limits usually manufactured, without special provisions therefor, or the necessity of having 30 containers of dimensions corresponding to the different sizes of records.

Another object of this invention is to provide a filing device of this nature wherein the containers may be supplemented by additional containers; or, such containers as are already in the file may be removed from the same in the simplest possible manner, although it will be impossible for any of such record holders to become accidentally 35 displaced from their proper place.

A further object of my invention is to provide a filing device in which all records may be arranged in alphabetical sequence according to the title of the same, which 40 device permits this scheme to be carried out irrespective of the number of records in use, and irrespective of the number of records and record containers that might be added to the original contents of the cabinet.

50 As illustrating my invention, I have appended hereto two sheets of drawings, in which—

Figure 1 is a front elevational view of a cabinet including a record file constructed 55 in accordance with my invention;

Fig. 2 is a sectional side elevation taken along the lines A—A of Fig. 1;

Fig. 3 is a side elevational view of an individual container;

Fig. 4 is a front view thereof; and 60

Fig. 5 is a section taken on the lines B—B of Fig. 3.

In the views, 1 designates the cabinet, which is provided with a floor 2, side walls 2', and a door (not shown). This cabinet 65 may support a talking machine, or may be the base of one, similar to the provision of shelves in the lower part of cabinet talking machines as they are at present constructed.

The record-receiving part of the cabinet is 70 preferably partitioned off from the rest of the same by means of the top panel 3', below which is mounted a horizontally-extending strip 3 formed with notches, such as 5, for the purpose hereinafter more specifically referred to. A further horizontal strip 4 is positioned below and to the rear of the horizontal strip 3 and has its longitudinal faces 75 extending in a plane out of the vertical.

A base block 6 extends through the entire 80 length of the cabinet 1 and may be spaced from the floor 2, as indicated at 7. The block 6 includes on its upper face an inclined portion 8 from which extends rearwardly a horizontal surface 9, the rear part of which 85 is provided with notches 10. A rounded grooved portion 11 is formed on a plane slightly above that of the horizontal surface 9, such grooved portion extending slightly upward through its entire length and forming at its upper end an apex 12 between it and a seat, including a downwardly extending plain surface 13 from the lower end of which an upwardly inclined portion 14 extends to the rear wall 15 of the block 6. 95

Individual containers 16 are formed of any suitable material, preferably heavy paper stock, or composition, which may be cut from a single sheet folded to assume the form indicated, such as to include a rear 100 wall 17, a front wall 19, and side walls 19'. The upper edges of the container 16 are left open, as indicated at 20, such upper edges extending parallel to the lower edges 18 through a certain portion of their length, 105 but being moved slightly, as indicated at 21, toward the base of the container. The container is left open at the base or lower edges 18 except for the block 27, hereinafter described. The container is further provided 110

with a notch, or cut out part 22 extending between the uppermost portion of the front end of the container to the outermost part of the upper edges 20, for the purpose herein-
5 after more particularly specified. A wooden block 24, positioned within such container, extends between the front wall 19 and the lower edge thereof. Secured to the block is a pull 25 provided with a hand knob 26, which
10 pull 25 depends from the lowermost position of the front end wall downwardly.

A block 27 provided with an opening 28 is secured to the base 18 between the side walls 19', as indicated at 29, a rod 30 being
15 adapted to extend through such opening and the openings of other containers, as indicated in Fig. 1 of the drawings. An essential feature in the form of block 27 is that 29' be a narrow plane surface parallel
20 to the base 18 and in width equal to the thickness of the container between the side walls 19' such as to provide a surface upon which a disk record smaller than the maximum size, that may be accommodated, may roll freely backward or forward within the limits determined by the rear wall 17 and the front wall 19 of the container in the manner illustrated in Fig. 2, also that the other dimensions conform to parts 14 and 15 of
25 block 6 as illustrated in Fig. 2. As will be noted upon reference to Fig. 1, rod 30 is provided with a pointed end, as indicated at 31, and such rod is adapted to act as a pivot for and tends to hold the container slightly
30 spaced from the base block 6, as indicated at 32 in Fig. 2. In this connection, it is to be noted that the surface 21 is cut on the curve, coinciding with an arc of a circle whose center is the center of the pivot opening 28.
35 It will be appreciated that too great a strain might be thrown upon the pivot blocks 27, by reason of the fact that three or four containers might be positioned in one of the rows in the cabinet and a slight jar
40 would place one of such containers slightly out of the vertical. This container would bear against its next container, and although the weight of one container would be inconsequential, five or six of such containers, all bearing one against the other would, together with the weight of their housed records, exert a considerable side strain upon the outermost container and, consequently, its block 27. To overcome
45 this difficulty, I have provided a movable partition including a rod mounting a board 34 adapted to engage the side edges of the outermost container, the ends of such rod 33 being adapted to seat in the notches 5 and 10. The board 34 engages the side walls of the outermost container, whereby any strain will be taken up by the partition instead of being thrown upon the pivot block 27.
55 In operation, it will now be seen that the

containers normally rest in the position indicated in full lines in Fig. 2, by reason of the fact that in this position the outer door of the cabinet may be closed, and such container rests with its rear edge against the 70 horizontal strip 4. It will be seen that in this position the labels, adapted to be applied as indicated at 35, will be inclined upwardly so that the same may readily be read.
75

If it is now desired to withdraw one of the records from its container, a pull upon the hand knob 26 will cause the container 16 to be rocked about the pivot rod 30, causing the container to assume an inclined position, as indicated in dotted lines in Fig. 2.
80

Should it become necessary to renew, add, or withdraw one of the containers completely from the file, all that it will be necessary to do will be for the rod 30 to be 85 pulled out of the cabinet 1 by means of its knob 36. All of the containers will drop slightly and rest, in this position indicated in full lines in Fig. 2, directly upon the base block 6 by means of their pivot block 27, 90 which will project into the rest 13 and 14. After removal or additions to the file have been made, the rod 30 may be again inserted and the pointed end thereof will engage the uppermost portion of the openings 28 and 95 cause the entire container to ride upwardly, until the pivot block 27 is again spaced from the base block 6, as indicated at 32.

The strip 34 may of course be entirely dispensed with when enough containers are 100 within the cabinet to make it possible for the outermost of the containers to engage the opposite side wall of the cabinet, or when so few containers are therein that no appreciable strain would be exerted upon 105 the outermost container even if the other containers did move slightly out of the vertical.

It will be further understood that such modifications as may seem practicable may 110 be resorted to without departing from the scope of my invention.

Having now described the said invention, what I desire to claim is:

1. A record cabinet including a number 115 of independent containers, blocks provided with openings secured to the lower portion of such containers, a base block positioned below the container blocks, and a rod provided with a pointed end adapted to pass 120 through the latter blocks and to act as a pivot therefor, such blocks being spaced from the base block when the rod is in proper position but being adapted to rest upon the upper face of the base block upon 125 the removal of said rod.

2. A record cabinet, including a base block, the upper surface of such base block having an apex and trough portion, such surface being inclined upwardly adjacent 130

the forward edge of the block, an envelop, a block forming a part of such envelop, and means associated with such block for permitting a rocking of the same, such block being adapted to be positioned above the apex in the upper surface of the base block, and being adapted to project within the

trough portion of the base block when the envelop is in its rearmost position, the envelop bearing against such forwardly located inclined surface when the envelop is in its forward position. 10

ROBERT McCART, JR.
